United States Patent Office

Des. 217,346
Patented Apr. 28, 1970

217,346

ELECTRONIC INSECT LAMP

Dan M. Andre, 8843 Kastner Terrace,
Skokie, Ill. 60076

Filed May 27, 1969, Ser. No. 17,378

Term of patent 14 years

Int. Cl. D22—09; D26—03

U.S. Cl. D22—19

Fig. 2

FIG. 1 is a perspective view of an electronic insect lamp embodying my design;

FIG. 2 is a top plan view of the same;

FIG. 3 is a side elevational view of the same; and

FIG. 4 is a bottom plan view of the same.

The side elevational view of FIG. 3 is the same for the other three sides of the lamp.

I claim:

The ornamental design for an electronic insect lamp, substantially as shown and described.
